UNITED STATES PATENT OFFICE

RICHARD FEIBELMANN, OF RADEBEUL, GERMANY, ASSIGNOR TO CHEMISCHE FABRIK VON HEYDEN, A. G., OF RADEBEUL, NEAR DRESDEN, GERMANY, A CORPORATION OF GERMANY

COMPOSITION OF BLEACHING AGENTS

No Drawing. Application filed October 25, 1928, Serial No. 315,107, and in Germany March 1, 1928.

This invention relates to bleaching agents and it particularly relates to dry mixtures of such bleaching agents, which can be conveniently stored and shipped in suitable containers and only when they are dissolved in water, yield solutions suitable for bleaching and the action of which is based on the splitting off of active chlorine upon their coming in contact with water.

With this end in view I mix the known dichlorides of aromatic sulfoamides, such as for instance p-toluenesulfodichloramides, with a salt of alkaline reaction, such as dry sodium carbonate, sodium triphosphate, borax, or the like alkali metal salts. The mixtures of these aforesaid substances are perfectly inactive when dry, but when dissolved in water these alkaline salts react with the dichlorides of these aromatic sulfoamides.

It appears that by dissolving the aforesaid mixture of the p-toluenesulfodichloramide and of a sodium salt of alkaline reaction the dichloramide is transformed into one molecule of the sodium p-toluenesulfochloramide and one molecule of sodium hypochlorite. A solution containing this mixture has a two-fold advantage insofar as its content of the generated sodium hypochlorite causes it to act at the usual temperature and the presence of the sodium p-toluenesulfochloramide exerts a slow bleaching action, often only when heated to an elevated temperature. The solutions obtained from these dry mixtures combine, therefore, the virtues of these two types of bleaching agents.

I am aware that it has been tried to bleach textile materials, such as wool, silk and the like, or fabrics made of the same, first at the usual temperature with an aqueous solution of sodium hypochlorite, and subsequently at an elevated temperature with an aqueous solution of the sodium-salt of p-toluenesulfodichloramide.

My new invention, however, is based on the fact that I produce stable dry mixtures, which, upon their being dissolved in water, exert the combined bleaching effect of both the alkali metal-hypochlorite and of the alkali metal salt of p-toluenesulfochloramide.

Inasmuch as mixtures of these two par-

ticular substances, however, cannot be produced in stable form, particularly as alkali metalhypochlorites easily undergo decomposition, there was, therefore, no way to manufacture dry stable mixtures of bleaching agents for the intended purpose.

It is therefore the essence of my invention that I am able to produce such stable mixtures by adding to p-toluenesulfodichloramides, and analogous compounds, dry alkali metal salts of alkaline reaction and that these mixtures only allow the formation of the bleaching agents upon their coming into contact with water.

The ingredients of the mixture may be brought together in stoichiometrical proportions, or one or the other substance, for instance the alkaline salt, may predominate.

Instead of p-toluenesulfodichloramide I may use as well the dichloramides of other sulfonic acid, for instance of the benzene-sulfonic acid, the naphthalene-sulfonic acid and other homologous acids.

The following example shows how I proceed in carrying my invention into effect:

Example

I mix 1 part of dry p-toluenesulfodichloramide, 4 parts of calcined sodium carbonate and to make a stock solution I dissolve the mixture in 8-10 parts of water. I have found that in laundry work a particularly beneficial effect is obtained if the aforesaid stock solution is diluted 3 to 5 times its volume.

What I claim is:

1. A solid and stable bleaching agent consisting of a dry mixture of a dichloride of an aromatic sulfoamide and of a water-soluble salt of alkaline reaction, which mixture, when treated with water, yields a bleaching solution containing an hypochlorite.

2. A solid and stable bleaching agent, consisting of a dry mixture of dichloride of an aromatic sulfoamide and of an alkali metal salt of alkaline reaction, the mixture, when treated with water, yielding a bleaching solution containing an hypochlorite.

3. A solid and stable bleaching agent, con-

isting of a dry mixture of p-toluenesulfodichloramide and of a water-soluble salt of alkaline reaction, said mixture, when treated with water yielding a bleaching solution containing an hypochlorite.

4. A solid and stable bleaching agent, consisting of a dry mixture of a p-toluenesulfodichloramide and of an alkaline metal salt of alkali reaction, the mixture when treated with water, yielding a bleaching solution, which contains an hypochlorite.

5. A solid and stable bleaching agent, comprising a dry mixture of p-toluenesulfodichloramide and sodium carbonate, said mixture yielding a bleaching solution when treated with water.

In testimony whereof I have hereunto set my hand.

RICHARD FEIBELMANN.
